(57) **CLAIM**

The ornamental design for a pan for a weighing device, as shown and described.

DESCRIPTION

FIG. 1 is a front perspective view of a first embodiment of the pan for a weighing device;

FIG. 2 is a front elevation view thereof;

FIG. 3 is a top plan view thereof;

FIG. 4 is a rear elevation view thereof;

FIG. 5 is a bottom elevation view thereof; and,

FIG. 6 is a left-side elevation view thereof, the right-side elevation view being a mirror image thereof.

The portions of the pan for a weighing device depicted by broken lines in FIG. 5 form no part of the design.
